Primary Examiner — Marcus Jackson(74) *Attorney, Agent, or Firm* — Banner & Witcoff, Ltd.**(57) CLAIM**

The ornamental design for a light bulb, as shown and described.

DESCRIPTION

The FIGURE is a front perspective view of a light bulb showing my new design. The broken line showing of the disclaimed elements inside the light bulb and the broken line showing of the remainder of the light bulb and the base are for environmental purposes only and form no part of the claimed design.

1 Claim, 1 Drawing Sheet(56)
